CLAIM

The ornamental design for a pan corner, as shown.

DESCRIPTION

FIG. 1 is a perspective view of the top of a pan corner showing my new design;

FIG. 2 is a top plan view thereof;

FIG. 3 is an additional top perspective view thereof;

FIG. 4 is a sectional view taken along the lines 4—4 of FIG. 2;

FIG. 5 is a sectional view taken along the lines 5—5 of FIG. 2;

FIG. 6 is a sectional view taken along the lines 6—6 of FIG. 2; and,

FIG. 7 is a sectional view taken along the lines 7—7 of FIG. 2.

The broken line showing of the remaining parts of the pan in FIGS. 1-7 is for illustrative purposes only and forms no part of the claimed design.
